CLAIM

The ornamental design for a storage and display rack, as
shown and described.

DESCRIPTION

FIG. 1 is a perspective view of a storage and display
rack showing our new design;

FIG. 2 is a left side elevational view, the right side being
a mirror image thereof;

FIG. 3 is a front elevational view, the rear being a mir-
ror image thereof;

FIG. 4 is a top plan view thereof; and,

FIG. 5 is a bottom plan view thereof.

FIG. 1.FIG. 2.FIG. 3.

FIG. 4.

FIG. 5.
